UNITED STATES PATENT OFFICE.

RUDOLF HUNDAUSEN, OF WILMERSDORF, NEAR BERLIN, GERMANY, AS-
SIGNOR TO THE SIEMENS & HALSKE ELECTRIC COMPANY OF AMERICA,
OF CHICAGO, ILLINOIS, A CORPORATION OF ILLINOIS.

THERMAL CUT-OUT OR FUSE FOR ELECTRIC CIRCUITS.

SPECIFICATION forming part of Letters Patent No. 738,908, dated September 15, 1903.

Application filed December 15, 1899. Renewed March 1, 1901. Serial No. 49,475. (No model.)

To all whom it may concern:

Be it known that I, RUDOLF HUNDAUSEN, a subject of the Emperor of Germany, residing at Wilmersdorf, near Berlin, Germany, have invented a certain new and useful Improvement in Thermal Cut-Outs or Fuses for Electric Circuits, of which the following is a full, clear, concise, and exact description, reference being had to the accompanying drawings, forming a part of this specification.

My invention relates to thermal cut-outs or fuses for electric circuits, and particularly to that class of fuses employing concentrically-arranged electrodes or terminals.

My invention has for its object the provision of an improved safety-fuse of the class described by the use of which the danger and the force of the explosion on the occurrence of a short circuit is materially decreased.

It has been customary in employing electric fuses, especially in connection with high-potential circuits, to inclose the terminal portions of the fuse-wires in cement, gypsum, or some other self-hardening insulating material, leaving the remainder of the wire exposed. Upon a rupture of a fuse due to an overload or short circuit explosions frequently occur, which scatter fine metallic particles and result in flames which tend to maintain a short circuit between the terminals of the ruptured fuse and which may short-circuit neighboring conductors.

In accordance with my invention I so construct fuse-plugs having concentric terminals that I decrease the harmful effects caused upon a rupture of the fuse by surrounding the immediate portion of the fuse-wire with talc or talcum powder, which I have found to be a substance that contains to a high degree

the power of readily absorbing the gases and metallic vapors resulting upon melting the fuses. I have heretofore devised an improved fuse employing talcum powder for the purpose of absorbing metallic particles that would otherwise be scattered upon the blowing of the fuse, and my invention herein relates more particularly to a new construction of a fuse in which talcum powder or some similar material possessing its characteristics is employed. There are additional features

of my invention which will be more fully set forth hereinafter.

I will more particularly explain my invention by reference to the accompanying drawings, in which—

55

Figure 1 is a vertical section through the center of a fuse-plug constructed in accordance with the invention, one terminal of the fuse being shown in complete elevation. Fig. 2 is a top view of the plug shown in Fig. 1, the cover being removed.

Like parts are indicated by similar letters of reference throughout both figures.

The plug-fuse shown comprises a hollow cylindrical base or shell *c*, having its lower end reduced and provided with an exterior metallic terminal *l*, threaded thereon, and a center metallic terminal *m*, located in a recess formed in the end thereof, and extending through the plug are a main-fuse wire *g* and a supplementary or indicator fuse wire *k*. One end of the fuse *g* is soldered to the terminal *l*, while the other end is soldered to a threaded extension of the central terminal *m*. The threaded extension of the terminal *m* passes through an axial bore in the bottom wall *d* of the shell *c*, a threaded washer or nut *n* engaging the threaded stem of the terminal *m* to secure the latter in place. Each fuse *g* and *k* is preferably looped, two division-walls *o* and *p* being interposed, respectively, between the sides of the looped fuse *g* and the looped fuse *k*. The terminal parts of the fuses are preferably embedded in gypsum or any suitable cement, while the middle portions of the fuses are embedded in talcum powder or other suitable material capable of absorbing the metallic vapor arising when the fuses are blown.

The partition-walls *o* and *p* as constructed serve, further, to reinforce the talcum powder to prevent metallic vapor from passing from one end of each fuse to the other. In the construction shown the central space between the partitions *o* and *p* is filled with talcum powder, which prevents metallic vapors from the fuse *k*, which is the last to be blown, from mingling with the metallic vapor due to the fuse *g*. The wall of the casing *c* of the fuse-plug is preferably of reduced 90

strength and thickness at one or more places, as indicated at *q*, so that the shell *c* will not be ruptured except at the weakened places upon explosions occurring when the fuses are 5 blown:

The fuse *k* is in the nature of a supplemental fuse and is preferably so constructed that it cannot possibly burn before or at the same time with the main fuse, it being desirable to 10 have it burn after the main fuse is blown. The desired result is accomplished by so constructing the supplemental fuse that an abnormal flow of current in the protected circuit that would cause a rupture of the main 15 fuse when divided between the same and the supplemental fuse would not cause a rupture of the supplemental fuse if the path closed by the main fuse were left intact, or, in other words, the same proportion of this abnormal 20 current initially flowing through the supplemental fuse would not in itself be sufficient to burn the same, so that the supplemental fuse cannot possibly burn until the main fuse is blown. The purpose of the supplemental 25 fuse is to serve as an indicating means whereby the working condition of the main fuse may be determined, and in order to permit the supplemental fuse to be seen I preferably locate the same before an opening *r* in the wall of 30 the fuse-casing, a small portion of the gypsum or cement being removed from the space between the supplemental fuse and the opening.

It is evident that a number of different applications may be made of the invention herein 35 shown and particularly described without departing from the spirit thereof, and I do not, therefore, wish to be limited to the precise construction shown.

Having thus described my invention, I 40 claim as new and desire to secure by Letters Patent—

1. In a fuse-plug, the combination with an inclosing shell, of an annular circuit-terminal carried thereby, a second terminal arranged substantially concentric with the aforesaid terminal, a fuse-wire uniting the terminals, and talc or other suitable powdered material within the casing and surrounding the fuse-wire, the insulating-shell being provided with a portion of reduced strength, whereby upon an explosion this portion will be the first to be ruptured, substantially as described.

2. In a fuse-plug, the combination with a 55 hollow cylindrical shell, composed of insulating material, of an annular terminal carried thereby, a second terminal substantially concentric with the annular terminal, also carried thereby, a main fuse uniting the said terminals, a supplemental fuse of less capacity, also uniting the said terminals, the wall of the casing being constructed to permit of the observation of the supplemental fuse, and talc or other suitable powdered material 65 within the hollow of the shell surrounding the fuse-wires, substantially as described.

3. In a fuse-plug, the combination with a

hollow cylindrical shell, of two terminals carried thereby, a main and a supplemental fuse wire uniting the said terminals, the said 70 fuse-wires being bent in the form of loops, a partition-wall interposed between the sides of each loop, and talc or other suitable powdered material within the hollow of the cylindrical shell surrounding the fuse-wires, substantially as described. 75

4. In a thermal cut-out, the combination with an inclosing hollow shell provided with an opening, of a main fuse and a supplementary fuse within the shell, the latter fuse 80 being visible from the exterior through the opening, a projection in the interior adjacent the supplementary fuse, a suitable material for blocking the passage from the hole in the shell to the interior between the shell and 85 the projection.

5. In a device of the class specified, the combination of a cylindrical casing having an inner wall arranged near one of its sides and also having an aperture in its outer wall opening into the passage between said inner wall and outer wall, a central terminal extending into the interior of the casing, and an annular terminal surrounding the exterior of the same, a loop-fuse extending between terminals and having its legs arranged on opposite sides of the said wall of the casing, and a body of talc or other suitable powdered material within the casing and associated with the fuse, substantially as described. 90 95

6. In a device of the class specified, the combination of a shell or casing having an inner wall arranged near its outer wall, an interior central terminal and an exterior annular terminal, a loop-fuse extending between terminals and having one of its legs extending into the passage between said walls, and cement arranged within said passage the shell or casing having an aperture affording an opening to the space between it and the 100 interior wall, and the cement being arranged to permit the fuse to be seen through said opening, substantially as described. 105

7. In a device of the class specified, the combination of a shell or casing having interior walls arranged near its sides and having an aperture in its outer wall opening into the passage between the same and the adjacent inner wall, an interior central terminal and an exterior terminal surrounding 115 the casing, main and supplemental fuses extended between terminals, the said fuses being looped and arranged so that one leg of each fuse extends through the passage between one of the inner walls and the outer 120 wall and the supplemental fuse being arranged in the passage into which the said aperture opens, cement within said passage, and absorbing material within the casing and associated with the fuses, substantially as de- 125 scribed. 130

8. In a fuse-plug, the combination of an insulating base or shell provided with a portion of reduced strength, metallic terminals

supported by said base or shell, and a fuse-wire extending through said base or shell and attached at its ends to said contacts.

9. In a fuse-plug, the combination of an insulating base or shell of insulating material, a center terminal and a concentric annular terminal secured to said base or shell, main and supplemental fuses connecting said terminals, and provisions in the wall of said

base or shell whereby observation of the supplemental fuse is permitted.

In witness whereof I hereunto subscribe my name this 24th day of March, A. D. 1899.

RUDOLF HUNDHAUSEN.
